BODY SUPPORT AND WEIGHT
DISTRIBUTOR

Ernest G. Dustin, near Galva, Ill.

Application October 3, 1949, Serial No. 119,283

8 Claims. (Cl. 155—198)

1

My present invention relates to means for supporting a portion of the weight of the upper part of the human body, other than by means of the spinal column. Primarily, the structure of this invention is for the use of those driving motor vehicles and particularly those who have to make long drives, although it is also useful to persons who, because of sickness or weakness from other cause, find it difficult or painful to support the body in an erect position. Among the objects of this invention are the provision of an apparatus which can be utilized to support a part of the weight of the upper portion of the human body by means of more or less rigid props engaging under the arms of the user; the provision of an apparatus of the type indicated which can move, readily, to various positions to accommodate the shifting of the body; and such further objects, advantages, and capabilities as will hereafter appear and as are inherent in the construction disclosed herein. My invention further resides in the combination, construction, and arrangement of parts illustrated in the accompanying drawings and, while I have shown therein what is now regarded as the preferred embodiment of this invention, I desire the same to be understood as illustrative only and not to be interpreted in a limiting sense.

In the drawings annexed hereto and forming a part hereof,

Fig. 1 is a view of one form of the present invention in use by an individual in a sitting position;

Fig. 2 is an elevation thereof;

Fig. 3 is a section taken substantially along the plane indicated by the line 3—3 in Fig. 2;

Fig. 4 is a plan of the base portion;

Fig. 5 is a detail section taken substantially along the plane indicated by the line 5—5 in Fig. 4;

Fig. 6 is a vertical section of the head portion of a modified form of the structure shown in Fig. 3;

Fig. 7 is a longitudinal section of the lower portion of a modified form of the structure shown in Fig. 3;

Fig. 8 shows another form of the arm loop, partly in section;

Fig. 9 is an edge view of the form of arm loop shown in Fig. 8; and

Fig. 10 is a partly sectional elevation of a still further modified form of the props.

The present invention comprises a base 1, to which is pivoted a pair of arms 2 to support the subject under the armpits, and a harness 3 to secure the upper ends of the arms 2 in desired position.

2

The base 1 is constituted of a rigid plate 4 upon which there may be positioned a seat pad 5. A bracket 6 is secured to the plate 4 to depend at its forward edge. This bracket 6 prevents rearward movement of the base 1 when the device is in use, with the base 1 positioned on the seat of a truck, tractor, or the like.

The arms 2 are connected to the base by ball and socket joints 7. These joints 7 are constituted of sockets 8 which are secured to the plate 4 at either side thereof in any of a plurality of holes 9. Rods 10 are provided at their lower ends with balls 11 of a size to be received and fit within the sockets 8. Each rod 10, as shown in Figs. 3 and 5, is provided with a flange 14 thereabout in proximity to the ball 11. A ring 15 is threadedly engaged in each socket 8 above the ball 11, whereby to retain the ball within the socket.

The sockets 8 and retaining rings 15 are provided with notches 16 of a width to receive the portion of rod 10 between the ball 11 and the flange 14. The flange 14 is spaced from the ball 11 sufficiently to clear the socket 8 when the rod is pivoted into the notches 16. The threaded ring 15 is of a thickness less than the distance from the ball 11 to the flange 14 whereby, for assembly, the ring 15 may be placed upon the rod 10, between the ball 11 and the flange 14, and then screwed into the socket 8. Although the notch 16 cuts completely through the retaining ring 15, the bearing of ring 15 upon the ball 11 prevents collapse of the ring 15 under load.

The arms 2 further comprise a pair of tubes 17 and 18, one slidable within the other. The outer tube 17 is provided with a thumb screw 17a, at its lower end, for maintaining the inner tube 18 in adjusted longitudinal position. The inner diameter of the inner tube 18 is such as to receive rod 10 in readily slidable engagement.

A U-shaped bracket 19 is secured to the upper end of each outer tube 17. A soft cylindrical pad 20 is rotatably secured between the arms of the bracket 19, and the pads 20 are proportioned to be received under the armpits of the user to give support to the body. A resilient tubular shoulder retaining strap 21 is secured at its ends to the extremities of the arms of the bracket 19. In order to hold the straps 21 on the user's shoulders, a harness 3 is provided.

This harness 3 comprises a pair of shoulder pads 22 and a group of straps connecting the pads. The pads are pieces of soft leather, approximately square in outline, with one edge turned over into a loop 22a which surrounds the tubular shoulder straps 21. To these pads are secured the straps 23 which may be secured together in pairs, one behind the neck and the

other in front thereof. These can be adjusted in length to position the shoulder straps 21 properly in accordance with the size of the individual. The loops 22a are slidably adjustable with relation to the shoulder straps 21 to fit the structure to the individual.

In operation, the user may sit on the base 1 or the pad 5 and place the arms 2 in position with the pads 20 under the armpits and the straps 21 over the shoulders. The neck straps 23 should then be adjusted sufficiently tightly to hold the straps 21 on the shoulders. The tubes 17 and 18 should then be adjusted to give adequate support to the back and allow some of the load to be carried in suspension from the shoulders. When the user wishes to move to some other job, all that is necessary is to get up. The inner tubes 18 slide off of rods 10. By having a base 1 on each equipment, the user may then move to another job without the necessity of further adjustment.

In Figs. 6 and 7 is shown a modification of the support structure shown in Fig. 3. This has a lower section, as shown in Fig. 7, and an upper section, as shown in Fig. 6. The head portion is freely rotatably supported with relation to the outer tube 17 and has a central cross tube 30 held in adjusted position with relation to the angular rods 31 and 32 by set screws 33. The upwardly extending portions 34 of the rods 31 and 32 extend into the tubular member 35, which corresponds to the tubular member 21 of Fig. 3, and are held in position therein by set screws 36. Heavy sponge rubber 37 is wrapped around the tube 30 and secured in place, preferably by a wrapping of soft leather.

As shown at 8a in Fig. 7, the form of the socket 8 may be varied. Also, the supporting rods 31 and 32 may be replaced by a single rod 38, as shown in Fig. 8, in which a piece of hose, split along one side, as indicated at 39, surrounds the rod 38 and holds the tube 21 in place on the rod. The rod 38 is slidable through an arcuately bent metal tube which has a threaded stud welded thereto, which is adapted to be screwed into one end of the tubular member 17. During use, this structure has the loop at its upper end arranged at an angle to the direction of the tube 17, as shown in Fig. 9.

In Fig. 10 there is shown a modified form of latch for holding the parts 17 and 18 in adjusted position. This comprises a ring 40 surrounding the tube 17 and slidable lengthwise thereof between the heads 42 and 43. This is for the purpose of holding the spring 41 against the tube 17 so as to force the latching means into a hole 25 whereby to prevent relative longitudinal shifting of the parts 17 and 18.

It is of course understood that the specific description of structure set forth above may be departed from without departing from the spirit of this invention as disclosed in this specification and as defined by the appended claims.

Having now described my invention, I claim:

1. A body-support comprising a base for the user to sit upon, a pair of rods upwardly extending therefrom, one at each side of the user in sitting position, a pair of shoulder supports, each of which comprises a pad for positioning under the armpit, and a pair of tubes in lengthwise slidably adjustment, one within the other, with the pad carried from the upper end of the outer tube, the inner tube being freely slidably positioned upon said rod, and freely slidably removable therefrom, the above structure making

it possible for a portion of the weight of the upper body of the user to be suspended from the shoulders, and a strap means engageable with the pad and holding same connected to the shoulders of the user so that he can rise from the seat without previously detaching the pads from the tubes.

2. A body-support in accordance with claim 1 in which said rods are pivotally connected to said base by a universal joint.

3. For use in a device of the class described comprising a support and an arm adapted to be carried thereby for ready removal therefrom, a ball and socket joint for pivotally connecting said arm with said support, said joint comprising a socket adapted to be secured to said support, a rod having a ball upon one end thereof and a flange about said rod spaced from said ball, a retaining ring for threaded engagement in said socket to retain the ball therein, said ring being open at one side and said ring being sufficiently thin whereby said ring may be passed between said ball and flange to position said ring about said rod, said flange being spaced from said ball a distance sufficient to clear said socket upon pivoting of said rod, and a tube slidable upon said rod for bearing upon said flange.

4. A body-weight distributing apparatus, comprising a base-plate, a pair of uprights having universal connection with said base-plate, each upright having a cross-head embodying cushioning material for engaging under the arms of the user to support part of the weight of the body, a strap connected with each cushion to engage over the shoulders of the user and hold the cushioning member against displacement, and strap means engaging the first strap means and holding same in place on the shoulders of the user.

5. A body-support comprising a base for the user to sit upon, a pair of substantially vertical arms connected at their lower ends to said base in laterally spaced-apart relation, each of said arms including a pair of telescopically associated members, the lower of said members being connected with the base, the upper members being freely removable upwardly from the lower members, means at the upper ends of said upper members to receive the armpits of the user, and a shoulder-encircling means securely connected to the upper end of each of said upper members for operatively connecting said upper members with the user, whereby the latter may rise from the body support and move about without disconnecting the upper members from his body.

6. A body-support as set forth in claim 5 having means connecting the upper portions of said shoulder-encircling means to prevent the latter from becoming disconnected from the body of the user when said user rises from said base and the upper members are released from the lower members.

7. A body-support as defined by claim 5 having means for connecting the lower ends of said lower members whereby said arms may be swung downwardly, relative to the base, into a position substantially parallel to the plane of said base.

8. A body-support comprising a base for the user to sit upon, a pair of rods upwardly extending therefrom, one at each side of the user in sitting position, a pair of shoulder supports, each of which comprises a pad for positioning under the armpit, and a pair of tubes in lengthwise slidably adjustment, one within the other, with the pad carried from the upper end of the outer tube, the inner tube being freely slidably positioned upon

said rod, and freely slidably removable therefrom, the above structure making it possible for a portion of the weight of the upper body of the user to be suspended from the shoulders, and a strap means engageable with the pad and holding the same connected to the shoulders of the user so that he can rise from the seat without previously detaching the pads from the tubes, said rods being pivotally connected to said base by a universal joint, each of said universal joints being provided with slotted portions at one side to receive the lower end of the associated rod when the rods and tubes are swung into a position approximately parallel and adjacent said base.
